UNITED STATES PATENT OFFICE.

OSCAR E. KALLWITZ, OF CHICAGO, ILLINOIS, ASSIGNOR OF ONE-HALF TO THOMAS A. CAMERON, OF CHICAGO, ILLINOIS.

EXPLOSIVE ENGINE.

1,415,096.

Specification of Letters Patent.

Patented May 9, 1922.

Application filed March 5, 1919. Serial No. 280,725.

To all whom it may concern:

Be it known that I, OSCAR E. KALLWITZ, a citizen of the United States, and a resident of the city of Chicago, county of Cook, and 5 State of Illinois, have invented certain new and useful Improvements in Explosive Engines, of which the following is a specification.

My invention relates to improvements in 10 explosive engines, and has for its object the provision of an improved construction of this character which is of simple construction and efficient in operation.

Other objects will appear hereinafter.

15 The invention consists in the combinations and arrangements of parts hereinafter described and claimed.

The invention will be best understood by reference to the accompanying drawings 20 forming a part of this specification, and in which,

Fig. 1, is a vertical central section of an engine embodying the invention,

Fig. 2, a top plan view of the same, shown 25 partially in horizontal section,

Fig. 3, a medial horizontal section taken through the cylinder of said engine, and

30 Fig. 4, a horizontal section taken through the inner end of the sleeve valves of said piston.

The preferred form of construction, as 35 illustrated in the drawings, comprises a suitable crank case 5 having the usual crank shaft 6 operating therein and a cylinder 35 casing 7 projecting upwardly therefrom. The cylinder casing 7 is long enough to constitute two axially aligning cylinders, and carries a spark plug 8 at its outer end and is equipped with a suitable cooling jacket 9, as 40 indicated. A cylindrical sleeve valve 10 is adapted to reciprocate within the cylinder 7 and is open at both ends, said sleeve valve being connected by a connecting rod 11 with a crank pin 12 on the valve shaft 13, which 45 is geared by means of a sprocket chain 14 with the crank shaft 6, as indicated. Another sleeve valve 15 is adapted to operate within the sleeve valve 10, and is connected by a connecting rod 16 with crank pin 17 of 50 the valve shaft 13, as shown. The sleeve valve 15 is divided by a central partition 18 into outer and inner cylinders, and pistons 19 and 20 are arranged to reciprocate within these cylinders. Said pistons are connected 55 by a connecting rod 21 passing through par-

tition 18, and innermost piston 20 is connected by connecting rod 22 with the crank shaft 6, as shown. This arrangement leaves a dead air chamber between the heads 18 and 19, which has no particular function in connection with the operation of the engine. A charge intake pipe 23 leads into the outer end of the inner cylinder through a port 24 controlled by ports 25 and 26 in the sleeve valves 10 and 15, respectively. An exhaust 65 port 27 leads from the outer end of said inner cylinder and is controlled by ports 28 and 29 in valves 10 and 15, respectively, said exhaust port 27 being connected by a by-pass pipe 30 with an inlet port 31 communicating 70 with the outer end of the outer cylinder and controlled by ports 32 and 33 in the sleeve valves 10 and 15. An exhaust port 34 leads from the outer end of the outer cylinder, being controlled by ports 35 and 75 36 in the sleeve valves 15 and 10, and leads to an exhaust pipe 37, as shown. An inwardly extending cylinder head 38 is formed at the outer end of cylinder 7 and fits within the outer end of sleeve valve 15, constituting 80 the cylinder head of the outer explosive cylinder.

The arrangement is such that, during each cycle of operation, an explosive charge is drawn into the outer end of the innermost 85 cylinder through pipe 23, which leads to an ordinary carburetor, and ports 24, 25 and 26, which are brought into registration for this purpose at the proper time. The charge thus drawn into the inner cylinder is compressed therein, and when compressed is discharged through ports 27, 28 and 29, passing through pipe 30 into the outer end 90 of the outer cylinder through ports 31, 32 and 33, said ports being brought into registration at the proper time for this purpose, as will be readily understood. The ports 31, 32 and 33 then close, and the compressed charge is re-expanded in the outermost 95 cylinder by the succeeding movement of the piston 19. The charge is again compressed by the next movement of the piston 19 and is exploded by spark plug 8 at the end of such compression in the usual way. The power stroke of the piston 19 then takes place, operating the crank shaft 6 in the usual way. At the end of this power stroke, ports 34, 35 and 36 are brought into registration and thus 105 opened to permit exhausting of the burnt gases which are expelled from the outermost 110

cylinder by the next stroke of the piston 19. At the end of this exhausting or scavenging stroke of the piston 19 ports 31, 32 and 33 again open as before, to admit a new charge, 5 and the cycle of operations is repeated as above outlined. It will be observed that the new charge is repeatedly expanded and compressed, which tends to mix the combustible vapors or gases thoroughly with the air and 10 break up the same, tending toward efficiency in operation and economy in fuel consumption. Thus, while the outer cylinder operates on the four-cycle principle, and good scavenging is obtained, the incoming charge 15 is expanded and compressed before explosion, as in the two-cycle engine, and great efficiency and fuel economy obtained. The specific form and arrangement of parts is a simple and effective one for the purpose. 20 While I have illustrated and described the preferred form of construction for carrying my invention into effect, this is capable of variation and modification without departing from the spirit of the invention. I, 25 therefore, do not wish to be limited to the precise details of construction set forth, but desire to avail myself of such variations and modifications as come within the scope of the appended claims.

Having described my invention, what I claim as new and desire to secure by Letters Patent is:—

- 30 1. An explosive engine comprising inner and outer axially aligning cylinders separated by a partition; pistons operating in said cylinders; a piston rod connecting said pistons and passing through said partition; a by-pass connecting the outer ends of said cylinders; a charge inlet pipe leading into the outer end of said inner cylinder; suitable valves and charge exploding means arranged to draw a charge into the outer end of said inner cylinder and compress it and transfer said compressed charge through 35 said by-pass into the outer end of said outer cylinder and explode it and exhaust the products of combustion therefrom; and means for utilizing the motions of said pistons, substantially as described.
- 40 2. An explosive engine comprising two axially aligning cylinders separated by a partition; pistons operating in said cylinders; a piston rod connecting said pistons and passing through said partition; a by-pass connecting said cylinders; suitable sleeve valves and sparking means controlling the operation of said pistons and cylinders and arranged to permit of the drawing of an explosive charge into one of said 45 cylinders, compressing it and transferring said charge through said by-pass into said other cylinder and exploding it; and means for utilizing the motions of said pistons, substantially as described.
- 50 65 3. An explosive engine comprising inner

and outer axially aligning cylinders separated by a partition; pistons operating in said cylinders; a piston rod connecting said pistons and passing through said partition; a by-pass connecting the outer ends of said cylinders; a charge inlet pipe leading into the outer end of said inner cylinder; suitable sleeve valves and charge exploding means arranged to draw a charge into the outer end of said inner cylinder and compress it and transfer said compressed charge through said by-pass into the outer end of said outer cylinder and explode it, and exhaust the products of combustion therefrom; and means for utilizing the motions of said pistons, substantially as described.

4. An explosive engine comprising a crank case; a crank shaft in said case; a valve shaft geared to said crank shaft; a cylinder casting projecting from said crank case, said cylinder being long enough to constitute two cylinders; a sleeve valve reciprocating within said cylinder and operatively connected with said valve shaft; another sleeve valve reciprocating within said first mentioned sleeve valve and having a central partition dividing the same into outer and inner cylinders; pistons operating in said outer and inner cylinders; a piston rod connecting said pistons and passing through said partition; a connecting rod connected with the inner piston and with said crank shaft; an intake pipe leading into the outer end of said inner cylinder, there being ports in said sleeve valves controlling the same; a by-pass leading from the outer end of said inner cylinder to the outer end of said outer cylinder, there being suitable ports in said sleeve valves controlling said by-pass; an exhaust pipe leading from the outer end of said outer cylinder, there being suitable ports in said sleeve valves controlling said exhaust pipe; and a spark plug in the outer end of said cylinder and arranged to explode charges in the outer end of said outer cylinder, substantially as described.

5. An explosive engine comprising a cylinder casing long enough to constitute two cylinders; a sleeve valve reciprocating within said casing; another sleeve valve reciprocating within said first mentioned sleeve valve and having a central partition dividing the same into outer and inner cylinders; pistons operating in said outer and inner cylinders; a piston rod connecting said pistons and passing through said partition; a crank shaft; and an operative connection shaft on said inner piston, substantially as described.

6. An explosive engine comprising a cylinder casing long enough to constitute two cylinders; a sleeve valve reciprocating within said cylinder; another sleeve valve reciprocating within said first-mentioned sleeve valve and having a central partition

- dividing the same into outer and inner cylinders; pistons operating in said outer and inner cylinders; a piston rod connecting said pistons and passing through said partition; 5 a by-pass connecting said outer and inner cylinders; suitable valve ports and sparking means controlling the operation of said pistons and cylinders and arranged to draw a charge into the outer end of said inner cylinder and compress it and transfer said compressed charge through said by-pass into the outer end of said outer cylinder and ex- plode and exhaust products of combustion therefrom; a crank shaft; and an operative connection between said crank shaft and the 15 inner piston, substantially as described.
- In testimony whereof I have signed my name to this specification in the presence of two subscribing witnesses.

OSCAR E. KALLWITZ.
